R. H. LANSING

STEAM GENERATOR

Filed April 13, 1923

FIG. 1.

FIG. 2.

INVENTOR.
RICHARD H. LANSING
BY
Joseph J. O'Brien
ATTORNEY.

UNITED STATES PATENT OFFICE.

RICHARD H. LANSING, OF CHICOOPEE FALLS, MASSACHUSETTS.

STEAM GENERATOR.

Application filed April 13, 1923. Serial No. 631,861.

To all whom it may concern:

Be it known that RICHARD H. LANSING, citizen of the United States of America, residing at Chicopee Falls, in the county of 5 Hampden and State of Massachusetts, has invented certain new and useful Improvements in Steam Generators, of which the following is a specification.

This invention relates to improvements in 10 steam generators and its leading object is to provide a steam generator which will generate steam rapidly by means of heat generated electrically by immersed electrical heaters.

15 Another object of the invention is to provide an improved boiler construction, which will induce a thermo circulation therein.

With the above and other objects in view 20 the invention consists in certain new and useful constructions and arrangements of parts, clearly described in the following specification and fully illustrated in the accompanying drawings, in which:—

25 Fig. 1 is a vertical sectional view through my improved steam generator.

Fig. 2 is a horizontal sectional view showing hot water connections, whereby the boiler 30 may be utilized in a hot water heating system.

Referring to the accompanying drawings illustrating the practical embodiment of the invention 5 designates the wall of a boiler, which includes the base or bottom wall 6, 35 and the top wall or dome 7.

In the boiler an inverted conical member 8 is mounted, its lower and wider end or skirt 8^a being spot welded or riveted directly to the base portion of the main wall 40 5. The small end of the conical member 8 provides a reduced steam outlet 9, which is located centrally over the bottom. This conical member thus provides a steam generating chamber 10, which is maintained in 45 normal communication with the water space surrounding the member 8, by means of small holes or openings 8^b formed in the wall of the member 8.

A feed water pipe 11 extends through the 50 main wall 5 and through the conical wall 8 into the steam generating chamber 10.

The temperature of the water is raised and converted into steam by means of electrical heaters 12, of the resistance type, which are mounted in sockets provided in

the bottom flange wall 6. Current is supplied to these heaters, as by means of the wires 12^a.

By connecting a hot water pipe 13 with the outlet 9, a hot water heating system 60 may be operated, if the feed pipe is connected with the condensation end of the system.

By actual trial I have found that my improved steam generator will generate 65 steam very rapidly.

The inner end of each electrical heater carries the resistance unit and this is raised to a high temperature by means of the 70 energizing electrical current. The colder layers of water flow into contact with the electrical heaters, while the water contacting with the heaters after the average temperature of the contents of the boiler has been sufficiently raised, is converted into steam, 75 which rises through the reduced upper end of the conical wall, thus inducing a rapid circulation.

In Fig. 1 I show a method of controlling 80 the current to maintain any desired or predetermined steam pressure or temperature condition. A pressure device 20 communicates by means of the steam pipe 21 with the boiler and this device is provided with a driven rod 22 which controls the current 85 through the magnetic switch 23, which operates the rheostat 24, which directly controls the strength of the current through the heaters, so that a constant steam pressure or temperature condition may be maintained. 90

Having described my invention I claim:—

1. A steam generator consisting of a boiler having a bottom and a conical member therein providing a steam generating 95 chamber under the conical member and over the bottom, said member having normally open communication with the boiler, one end of the conical member providing an outlet, a feed water connection leading to said steam generating chamber, and an electrical heater projecting into the steam generating chamber.

2. A steam generating device consisting 100 of a boiler having a bottom and a steam generating chamber above the bottom and provided with an inverted conical wall having a reduced steam outlet on its upper end and inlet openings in its lower end, a feed water pipe connected with the steam gen-

erating chamber, and a series of electrical resistance heaters extending into said bottom and into the steam generating chamber.

5. 3. A steam generator comprising a boiler having a bottom wall, a series of resistance heaters projecting through the bottom wall, each of the heaters being provided with terminals supported exteriorly of said bottom wall, said boiler having a water inlet located near said heaters and a conical member arranged in said boiler and having its outer marginal edge portion secured to

the boiler and a normally open outlet extending upwardly of the boiler, said member being provided with a series of openings having normally open communication with the interior of the boiler and through which the water may freely circulate, said water inlet extending through said wall to deliver the cold water supply into the chamber established by said member within the boiler.

Signed by me at Springfield, Mass.

RICHARD H. LANSING.
